UNITED STATES PATENT OFFICE.

ERNST JÄNECKE, OF HANOVER, GERMANY.

PROCESS OF LIQUEFYING AIR AND SEPARATING IT INTO ITS ELEMENTS.

1,015,800.

Specification of Letters Patent. Patented Jan. 30, 1912.

Application filed October 27, 1909. Serial No. 524,998.

To all whom it may concern:

Be it known that I, ERNST JÄNECKE, a subject of the German Emperor, residing at 31 Ferdinand Wallbrechstrasse, Hanover, Germany, have invented certain new and useful Improvements in Processes for a Continuous Reproduction of Fluid Air and for a Continuous Separation of the Same into its Ingredients, of which the following is a specification.

The invention relates to a process for liquefying air and separating it into its elements.

An object of the invention is, to provide a more satisfactory process for the purpose stated than any of the previously known processes; and, by a continuation of the process, to separate the elements of the liquid air in an economical and thoroughly practical manner.

The basic principle of the invention is to direct cold compressed air into indirect contact with liquid (which is rich in oxygen); thereby causing the liquid to boil and the air to condense and liquefy.

In carrying the invention into effect, it is preferable to employ coils of pipe, or the equivalent, whereby a sufficient length of the pipe may be contained in tanks or vessels of convenient and economical size and shape.

When air, under a given heavy pressure is being forced through sufficiently cold coils of pipe, has been brought to the boiling temperature of liquid air and oxygen, a relatively slight extra pressure will cause the air to liquefy. While thus being converted from the gaseous to a liquid state, the heat given off by compressed air, in passing from the gaseous to the liquid state, will cause the liquid air in the vessel to boil, and part of such liquid air will pass off as vapor. Since the boiling point of nitrogen is lower than that of oxygen, the said vapor will contain a much larger percentage of nitrogen than oxygen, so that the percentage of oxygen left in the boiling liquid air will be increased. The liquid air, having thus been obtained, passes from the pipes into decomposing apparatus, which will hereinafter be described, for the purpose of elucidating the process.

The relatively low temperature of the elements of the decomposed liquid air is utilized in reducing the temperature of the com-

pressed air, as a preliminary step in the process of liquefying the air. During this process the two gases, used for cooling, become heated.

In brief, the process consists in pumping compressed air, of ordinary temperature, into an apparatus which has previously been primed with liquir air, and after being decomposed into its constituent elements, these elements are delivered by the apparatus at approximately the same temperature at which the air was introduced. The liquid air thus obtained is almost the same in quantity as that initially employed for priming the apparatus.

In carrying out the process, I preferably employ the apparatus described in the following, and as illustrated in the accompanying drawing, in which the figure is a diagrammatic vertical sectional view of the preferred form of apparatus.

The different parts of the apparatus will be referred to by reference characters appearing on the drawings; a' being the boiling vessel, containing liquid, rich in oxygen. a^2 is a vessel containing almost pure oxygen. b is an outlet cock for controlling the communication between said vessels. Coils of pipe q' and q^2 act as vapor outlets for the vessels a' and a^2 respectively; the first, communicating directly and the latter, indirectly through the portions of pipe h^2 , h' , coils f' or f^2 and the chamber c^2 . Through the coils q' , q^2 extend smaller pipes r' and s' respectively. These pipes communicate with an air supply pipe t , and extend through the said vessel a' and a^2 , in the form of coils r^2 and s^2 , a portion of their length being coiled within the vessel. The end of each air supply pipe is connected to a receiving vessel p' , which communicates with a primary charging vessel p , through the pipe u , to which is fixed a pressure gage v , and a pressure regulating cock b^s . By means of this cock b^s only a relatively small port, for the entry of liquid air into the vessel p' , is provided; and it may be adjusted according to the pressure desired to be sustained in the pipes t and u . The liquid air passes through the cock b^s into the vessel p' under high pressure; the pressure being reduced in the vessel p' , a small portion of the liquid air is vaporized and passes off through the coiled pipe w . The pipe u enters the pipe w through a side thereof, and

enters through a portion of the coil thereof, and thence out through the side of the pipe w and connects with the cock b^s and thence enters the vessel p' . The pipes u and w , in the relation described, constitutes a heat exchanger, whereby the temperature of the liquid air, entering the vessel p' is slightly lowered and the temperature of the gas, escaping through the pipe w is raised.

10 The vessel p' is provided with a pipe x , through which the priming liquid is introduced, and this liquid gravitates through the two-way valve b^4 into the cooling vessel k' , and thence through the two-way valve b' and pipe e , into the boiling vessel a' , whence it is admitted through the stop-cock b , into the vessel a^2 . The vessels k' and k^2 have vapor outlet pipes o' and o^2 which connect with the suction pipe o^3 through the two-way valve b^3 .

15 It is obvious that by reversing the positions of the valves b^4 and b' , the priming liquid gravitates through the cooling vessel k^2 instead of through the vessel k' . These vessels k' and k^2 are provided with pressure gages m' and with floats i' which constitute depth gages.

20 It may be well to consider the operation of the apparatus in connection with the process. Let it be assumed that, as an initial step, the apparatus has been primed, through the pipe x , the valves b^4 and b' being in the opposite positions to those shown in the drawing, each of the vessels k' and k^2 being partially filled with liquid air, and that as a secondary step in the operation, their positions have been reversed to the positions shown. Atmospheric air is next introduced, under pressure, through the pipe t , and suction means (not shown) is applied to the pipe o^3 , for a purpose hereinafter explained. The compressed air from the pipe t , in passing through the pipes r' and s' and coils r^2 and s^2 , causes the liquid in the vessels a' and a^2 to boil; and the oxygen gas from the vessel a^2 passes out through the pipe q^2 , which surrounds the pipe s^2 , and by its contact therewith, lowers the temperature of the air therein and prepares it for the lower temperature of the liquid in the vessel a^2 . The liquid, surrounding the coil of pipe s^2 causes the compressed air therein to condense, liquefy and precipitate in the vessel p^2 , whence it is elevated through the pipe u and cock b^5 and enters the vessel p' and thereby continually adds to the primary working charge of the apparatus; the elevation of the liquid being effected by means of the air pressure through the pipes t and r' and s' . The relatively high temperature of the air, being conducted through the coil r^2 , causes the liquid in the vessel a' to boil the more.

25 By reason of the partial evaporation which takes place in vessels k' and k^2 , the

liquid which passes in the vessel a' is rich in oxygen, that is; the percentage of oxygen in the liquid is greater than in atmospheric air.

As the boiling point of nitrogen is lower than that of oxygen, the percentage of nitrogen in the vapor will be greater than in the liquid. This vapor, as it passes through the coil f' or f^2 will tend to condense, owing to the very low temperature of the liquid air in vessel k' and k^2 which is being evaporated at low pressure. The vapor liquefied in coil f' or f^2 falls into the trap h' , where, owing to the higher temperature, some of the liquid is again evaporated and passes off through the pipe h^2 , coil q' and pipe t' ; but the major portion of the liquid re-enters the boiling vessel a' , through the chamber c^2 , while the nitrous gas rises in the chamber h and passes out through the pipe h^2 and q' ; and in passing through this coil q' it lowers the temperature of the air in the pipe r' , by its contact therewith, and thus prepares the air for more accelerated condensation in the coil of the pipe r^2 , and its precipitation into the vessel p^2 , whence it continually passes (as heretofore explained), into the vessel p' and thence to the cooling vessel k' . From this vessel it is admitted into the vessel a' through the two-way valve b' ; this valve being so regulated that the quantity of liquid leaving the vessel k' is less than the quantity entering it. Therefore, the quantity of liquid continually increases in the vessel k' while it continually decreases in the vessel k^2 , consequent to evaporation caused by the suction through the pipes o^2 and o^3 . The object of this suction is to relieve pressure on, and reduce the temperature of the liquid in the vessel k^2 ; thereby assisting the condensation of the gases and precipitation of the liquid in the coils f^2 . When the liquid in the two cooling vessels k' and k^2 has reached the respective levels shown in the drawing, it becomes necessary to reverse the positions of the two-way valves, and thereby divert the flow of gases and liquid, whereupon, the gases passing through the pipe d will enter the coil f' instead of the coil f^2 ; and the liquid from the vessel p' will enter the cooling vessel k^2 instead of k' . The process will thus be interrupted only during the operation of reversing the valves and will then be resumed in substantially the same rotation as described in the foregoing.

I claim—

20 A process of liquefying air and separating it into its elements, consisting of liquefying air under pressure by bringing it into indirect thermal contact with a liquid rich in liquid oxygen whereby the said liquid is made to evaporate, then bringing a given quantity of the liquid air so produced into

indirect thermal contact with the vapors given off by the liquid rich in oxygen, causing a part of said liquid air to evaporate at less than atmospheric pressure, thus causing a part of the vapors given off by the liquid rich in oxygen to reliquify, and then adding the part of the liquid air not evaporated and the liquid obtained by the par-

tial condensation of the vapors to the liquid rich in oxygen.

In testimony whereof, I affix my signature in the presence of two witnesses.
